(57) **CLAIM**

(21) Appl. No.: **29/301,193**

The ornamental design for a bucket stabilizer for cylindrical surface, as shown and described.

(22) Filed: **Feb. 19, 2008**

DESCRIPTION

(51) **LOC (9) Cl.** 07-07
(52) **U.S. Cl.** D32/54
(58) **Field of Classification Search** D32/53,
D32/53.1, 54; D23/206; 248/346.01
See application file for complete search history.

FIG. 1 is a perspective view of a bucket stabilizer for cylindrical surface, shown upside down for clarity of illustration; and,

FIG. 2 is a perspective view thereof, which has been drawn in correct orientation.

The broken line showing of a bucket is included for the purpose of illustrating and forms no part of the claimed design.
